CLAIM

The ornamental design for a grab bar for recreational vehicles, substantially as shown and described.

DESCRIPTION

FIG. 1 is a perspective view of a grab bar for recreational vehicles showing my new design.

FIG. 2 is a top plan view thereof.

FIG. 3 is a side elevational view thereof.

FIG. 4 is an end elevational view thereof.
The side and end opposite the respective side and end illustrated in FIGS. 3 and 4 are mirror images of the respective views.
